UNITED STATES PATENT OFFICE.

GEORGE GOULD GOING, OF MIDDLETOWN, CONNECTICUT, ASSIGNEE TO REMINGTON-
NOISELESS TYPEWRITER CORPORATION, OF NEW YORK, N. Y., A CORPORATION
OF NEW YORK.

TYPEWRITING MACHINE.

Application filed June 24, 1925. Serial No. 39,193.

My invention relates to typewriting or like machines and more particularly to type actions therefor.

The main object of the invention, generally stated, is to provide an improved construction and arrangement of parts whereby the elements of each type action are functionally and structurally coordinated to facilitate printing in an improved manner.

More specifically stated, one of the objects of the invention is to provide improved and highly efficient type actions for printing without producing the noise that ordinarily results from the operation of the type actions.

A still further object of the invention is to provide an improved and highly efficient construction of the character specified in which the type actions are controlled from a standard keyboard with a single shift.

Another object of my invention is to so construct and arrange the parts that each type block at the last portion of its printing movement will squarely enter a center type guide and effect an imprint with substantially a straightline movement.

A further object of the invention is to provide improved means for arresting the return movement of each type bar and the parts connected therewith in a substantially noiseless manner and without rebound.

To the above and other ends which will hereinafter appear, my invention consists in the features of construction, arrangements of parts and combinations of devices set forth in the following description and particularly pointed out in the appended claims.

In the accompanying drawings, wherein like reference characters designate corresponding parts in the different views,

Figure 1 is a fragmentary fore-and-aft central vertical sectional view, with parts omitted, of a Remington-Noiseless No. 6 typewriting machine embodying my invention;

Figure 2 is a side view of the type action shown in Fig. 1 as it is seen from the opposite side, and with the type bar projected

to printing position under an actuation of one of the two printing keys which control it;

Figure 3 is an enlarged fragmentary detail side view of a portion of one of the type actions with the parts disposed in normal position;

Figure 4 is a top plan view of the same;

Figure 5 is an enlarged fragmentary detail rear edge view of a portion of one of the type actions;

Figure 6 is a fragmentary detail rear view with parts in section showing a guide comb and the companion sublevers and driving lever of one of the type actions;

Figure 7 is an enlarged detail fragmentary front view of the center type guide with the type block shown in section entering the guide; and

Figure 8 is a diagrammatic view showing a portion of one of the type actions.

I have shown my invention embodied in the present instance in a Remington-Noiseless No. 6 machine, but have only shown so much of said machine as is necessary to arrive at an understanding of the invention in its embodiment therein. It should be understood, however, that the invention is not restricted to embodiment in such machine, but may be employed in typewriting or like machines generally, wherever found available.

The present invention has some of the same general objects in view as the structures disclosed in my copending applications: Sr. No. 665,290 filed Sept. 28, 1923, Sr. No. 3,365 filed Jan. 19, 1925, Sr. No. 7,941 filed Feb. 9, 1925, and is intended to improve the operation and in some respects render the type action more efficient and reliable in use, and may be regarded as an improvement on the constructions disclosed in said applications.

As in the constructions disclosed in my said co-pending applications, I provide in the present instance a machine having a standard keyboard of four banks of keys, each type bar carrying four types and being

operated by either one of two keys. Each pair of keys actuate a single front-stroke type bar in a substantially noiseless manner to normally selectively print from one or another lower case type on the type bar, depending on which of two keys is actuated, or to selectively print from one or another upper case type on the same type bar after a relative case shift has been effected between the platen and type bars.

In the present construction I have modified the means for controlling the paths of movement of each type bar so that each bar moves at the last portion of its printing stroke in substantially a straight line into the center guide, and to the printing point, as distinguished from a type moving in an up or down curved path throughout its travel to the printing point, as disclosed in my hereinbefore mentioned application, Sr. No. 3,365. This change provides for more accurate guiding of the type block and the provision of better alignment of the imprints.

In the present construction I also have provided improved and highly efficient means for substantially noiselessly arresting each type bar and the connected parts in their return to normal position, and for preventing rebound from such normal position.

In the present embodiment of my invention the frame of the machine may be said to include a base 1 and so-called frame member 2 on which various working parts of the machine, including the type actions, are supported. It will be understood that the type bars are arranged in a substantially horizontally disposed arc in front of and around the printing point as a center, so that each type bar moves but a short distance in a radial plane to the common printing center, as in the constructions disclosed in my said co-pending applications. The controlling means for each type bar, with the possible exception in some instances of the key levers therefor, move in the same plane as the plane of movement of the associated type bar, or as close to and parallel with such plane as the assembled parts will permit. With the foregoing general statement I will proceed to describe a single type action, it being understood that all actions are alike, or substantially so, except that they are mounted in different planes that radiate from the printing center. The description of one type action applies to the others.

Each type action comprises a flat substantially horizontally disposed type bar or type carrying member 3 provided with a plurality of type blocks 4 and 5 fixed thereto. The type block 4 has a lower case type 6 and an upper case type 6^a, whereas the type block 5 has a lower case type 7 for printing a different character and a companion upper case type 7^a, the printing

faces of the types on the two blocks being arranged in converging planes. Each type bar is guided against sidewise displacement in its printing movement by three fixed arc-shaped guide combs, a, a¹, a², having radial slots in which the type bars move. Each type bar is supported by a pair of links 8 and 9 pivoted respectively at 10 and 11 to the type bar at different points in the length thereof; the link 8 being pivoted to the type bar nearest the rear or type-carrying-end thereof. The link 8 extends as one continuous member from the pivot 10 down to the lower end of the link (see Fig. 5) where it is provided with a laterally projecting pivot pin 12.

A spring retaining member 8^a is riveted near one end to the link 8 and at the opposite end is spaced apart from the link and is adapted to bear on the free end of the pivot pin 12, and thus detachably connects the link 8 to the member on which the link is supported and pivoted. The lower end of the link 9 is mounted to turn on a pivot pin 13, and the links 8 and 9 are thus mounted to swing respectively on the centers of the pivots 12 and 13 in the movement of the type bar from normal to printing position. In the present construction the pivot pin 13 always remains fixed during the travel of the type bar to printing position, but the pivot pin 12 is arranged to be displaced from normal position as shown in Fig. 2, during the travel of the companion type bar under the actuation of one of its two printing keys. The pivot pin 12 is mounted on a controlling member 14 in a bearing-opening in which is received the pivot 12. In the present instance this member 14 is in the nature of a lever pivoted at 15 on a headed pivot pin secured to a type action bracket or hanger 16 on which all associated parts of the type action except the key levers are mounted and by which they are supported, it being understood that a separate hanger is provided for each type action.

The four-point supporting means for each type bar involving the pivots 10, 11, 12 and 13 I term a quaternate or quaternal linkage. The lever 14 in the present instance is angular in shape to avoid interference with other parts of the type action, as will be understood from an inspection of Fig. 2. The free end of this lever is pivoted at 17 to the upper end of a curved link 18 pivoted at its lower end, as at 19, to one arm of a bell crank lever 20. This last mentioned lever is pivoted at 21 on a stationary arm 22 that may be adjusted to different set positions on the companion hanger 16, as will hereinafter more clearly appear. The other arm of the lever 20 is pivoted at 23 to a link 24 pivoted at its upper end, as at 25, to a lever arm 26 pivoted at 27 on the associated hanger 16. The link 24 and lever arm 26 constitute two elements or

members of a toggle broken from its straight line position by one of the two printing keys of the type action and by which the position of the pivotal center of the link 8 is controlled. It will be seen that when the toggle is in the Fig. 1 substantially straight-line holding position, in which a straight line passes substantially through the pivots 23, 25 and 27, the pivotal center 12 will be held fixed at its highest elevation. However, when the toggle is broken to the Fig. 2 position the center 12 is lowered to a different elevation. It also will be observed from a comparison of Figs. 1 and 2 and from a consideration of Fig. 8 that in both these positions the center 12 is approximately on the same vertical line, and is at substantially equal distances respectively above and below a horizontal line passing through 20 the fulcrum 15 of the lever 14.

The diagram represented in Fig. 8 is intended to show the disposition of the links 8 and 9 and their pivotal points when the parts are in printing position under the actuation of either of the two associated printing keys. Referring particularly to this figure, it will be seen that due to the specific construction, and to the relative arrangement of the parts shown, a straight line *u* drawn through the pivots 10 and 12, when the last mentioned pivot remains fixed and companion type bar is in the printing position, will when extended, intersect a straight line *v* drawn through the pivots 11 and 13 of the link 9. This point of intersection *w* will be on a line *z* tangential to the platen at the printing point, and at a distance in the present instance of a little over four inches above the printing point. Moreover, this point of intersection *w* between the lines in question will be the same, or approximately the same, whether the pivot 12 be in the Fig. 1 or in the Fig. 2 position. This is indicated in Fig. 8 wherein the line *y* is shown passing through the pivots 10 and 12 (shown in dotted lines) when they have been moved down to their Fig. 2 position. The point of intersection *w* in question may be said to represent the instantaneous center on which the type bar moves near and to the printing point, and which gives a substantially rectilinear movement to the effective type near the printing point at the last portion of the printing movement of the bar. The substantially rectilinear movement in question is one in which the effective type, whether the type bar is actuated by one or the other of its two printing keys, moves substantially in a straight line which if projected would pass through the printing point and the axis of the platen, as indicated by the line *z*. Such movement enables the active type block to enter the center type guide *d* substantially square and in the direction of the line *z* instead of in a curved

path at an angle to such line as in the construction disclosed in my copending application Sr. No. 3,365 and provides for better guidance of the type blocks and a more perfect alignment of the imprints, as will hereinafter more clearly appear. It may be here pointed out, however, that this construction and arrangement of the linkage to secure the results stated is an important factor of the present invention. While the diagram shown in Fig. 8 represents a theoretically correct construction and disposition of the points to give the proper substantially rectilinear movement in question to the effective type as it approaches the printing point under the actuation of either of its two printing keys, it should be understood that in practice these points may be slidably deviated from without sufficiently interfering with such movement in question as to make it objectionable. For example, if the lines *u* *v* *y* should not all converge at the point *w*, or exactly on the tangential line *z*, good results may be obtained nevertheless. But the closer the approximation to the points indicated the better will the mechanism respond to the requirements pointed out.

I have hereinbefore pointed out that each type bar is operated selectively by two printing keys. One key automatically brings one of the upper pair and the other one of the lower pair of types on the type bar to the printing position. In practice I prefer to arrange the printing keys 28, 29, 30 and 31 in four banks, with the key 29 in the second bank and the key 31 in the fourth bank connected to one type action, as shown. The next type action will have its keys 28 and 30 in the first and third banks respectively connected to the associated type bar. In moving a type bar to printing position under the actuation of the key 29 the type 7 will follow a curved path indicated substantially by the dotted line *b*, if the parts have been properly adjusted. On the other hand, when the type bar is moved under the actuation of the key 31 the type 6 will follow a curved path of the general character indicated by the dotted line *c*. These curves are oppositely disposed and converge in front of and in line with the printing point, and complete their printing movement from thence to the platen substantially with a rectilinear movement substantially coincident with the line *z*, entering the type guide *d* squarely with such a movement. The means by which the paths of movement of a type bar are controlled include in part features which have been described, including the lever 14 by which the pivotal center 12 of the supporting link 8 may be shifted up and down from the Fig. 1 to the Fig. 2 position. I will now describe in detail how each type bar has its path of movement controlled from its two printing keys.

The key 31 is carried by a key lever 32 fulcrumed at 33 in the base of the machine and provided with an individual returning spring 34. This spring is adjustably connected at one end to a depending arm 35 on said key lever, and is connected at its other end with a bar 36 that extends beneath all of the key levers and is adjustably mounted by suitable means in the base of the machine. The key lever 32 is detachably connected to a link 37 by a pivot 38 carried by said lever and received in an opening in the lower end of said link. A side-bearing spring-plate or clip 39 is pivoted at 40 to the companion key lever and bears laterally at its free end against the link 37. This clip holds the link connected to the lever when the clip is in the effective position shown, and enables the link to be detached from the lever when the clip is turned down around its pivot 40. The upper end of the link is pivoted at 41 to an actuating member, sublever or lever arm 42 pivoted at 27 on the right-hand side of the bracket 16. This lever extends rearwardly beyond its pivot to form a second lever arm 26 which constitutes one member of the controlling toggle, as previously set forth. In order to limit the movement of a toggle member 26, and the parts connected therewith, in both directions, I provide an opening 43 in said member 26 to receive a stop pin 44 fixed to and projecting laterally from one side of the bracket 16. This stop pin co-acting with one side wall of the opening 43, as shown in Fig. 1, will limit the return movement of the member 26 and the parts connected therewith. This prevents the toggle 24, 26 in its return movement from breaking beyond the substantially straight-line normal position. The effect of maintaining the toggle in the substantially straight-line position, is to hold the pivot 12 quiescent in the position shown in Fig. 1 when the type bar is moved to the printing position by the actuation of the key 29. However, the depression of the key 31 results in moving the member 26 to the position shown in Fig. 2, where the opposite side wall of the opening 43 co-acting with the stop pin 44 limits the movement of said member 26 and the parts connected therewith including the key 31. This depression of the key 31 results in breaking the toggle from the substantially straight-line holding position, shown in Fig. 1, to the operated position indicated in Fig. 2, thereby lowering the pivotal center 12 of the type bar supporting link 8 to change the path of movement of the type bar to the printing position. The proper positioning of the pivot 12 in the Fig. 2 position, and the holding of it in such position by the toggle, is effected before the final printing movement of the type bar takes place.

The other printing key 29 of the type action shown is carried by a key lever 45 constructed, pivoted and individually spring returned like the key lever 32 previously described. The key lever 45 is connected to a link 46 in the same manner that the link 37 is connected to its key lever 32, and has its upper end pivoted at 47 to an actuating member or sublever 48. Said sublever is arranged at the opposite side of the hanger 16 from the lever arm 42 and is mounted to turn on an extension of the pivot 27. The lever arms 42 and 48 forward of the pivot 27 are parallel with each other and are of like construction, except that the arm 48 is provided with a depending lever arm 49. This arm 49 is pivoted at 50 to a link 51 which has its rear end pivoted at 52 to a lever 53. The lever 53 is pivoted at 54 on the left-hand side of the bracket 16 and is bent or off-set laterally to form a yoke portion 55 above the bracket and is thence bent downwardly to form a lever arm 56 on the left-hand side of said bracket and overlying the lever arm 26, for purposes which will now appear. From an inspection of Fig. 2 it will be seen that the lever arm 49 is provided with an opening 49^a, the walls of which coact with the stop pin 58 on the hanger 16 to limit the motion of the member 48-49 and the parts connected therewith in both directions, like the corresponding stops of the member 26, 42.

It will be understood that after each breaking of the toggle 24, 26 from the Fig. 1 to the Fig. 2 position by an actuation of the key 31, the returning spring 34 for said key is intended to return the toggle to normal straight-line position when the operator releases the key. However, it may happen at times that the toggle 24, 26 has not completely returned to such position before an actuation of the type bar by the other key 29 takes place. It is in order to rectify the position or insure the complete return of the toggle, and thus to maintain an accurate positioning of the pivotal center 12 in the Fig. 1 position, that I provide the lever 53, 56 operating in the manner described. Thus, it will be understood that a depression of the key 29 will, through the intermediate train of connections 46, 48, 49, 51, and 53, lower the arm 56. If the toggle 24, 26 had not been fully returned after the preceding operation of the type bar by the key 31, then the part 26^a of the member 26 will extend in the path of the arm 56, and as the latter is moved down under the actuation of the key 29 the member 26 will be forced to the limit of its return movement, or until it coacts with the stop 44 in the Fig. 1 position. This occurs before the type bar reaches the printing position under the action of the key 29, and insures the proper positioning of the pivotal 120

center 12, and insures that a proper imprint of the type at the printing point will result.

Thus far I have described the means by which each type bar is individually guided or controlled in its movement to travel in one curved path or another to the common point of convergence and moves from thence to the printing center in substantially a straight line to cause one or another type thereon to print in accordance with which of the keys 31 or 29 is actuated. But I have not described the driving means by which each type bar is moved to printing position.

In the present construction, like those disclosed in my said copending applications, I employ a single train of driving means or connections for each type action including motion governing means having a momentum accumulator, said governing means being arranged to decelerate the final printing movement of the type bar and to translate into pressure against the platen the kinetic energy of the accumulator. It is due to such means combined with the parts previously described that an imprint may be effected in substantially a noiseless manner. Operating motion is transmitted to each type bar from both of its printing keys through the above-mentioned single train of driving means, to actuate each type bar with a substantially uniform touch from both its keys and to provide a uniform, or substantially uniform, touch on the keys throughout the system.

It has been explained that the independently operating lever arms 42 and 48 forward of their common pivot 27 are of uniform character and are mounted to move in parallel planes. A main driving lever 57 is provided in each type action, this lever being pivoted at 57^a to a depending arm on the associated bracket 16. It will be understood that in the present instance I construct each of these levers from two correspondingly shaped members spaced apart and held together in spaced relation by suitable means, such as shouldered rivets. The construction of each of the driving levers and the connections therefrom to the type bar may be the same, or substantially the same, as disclosed in my hereinbefore mentioned application, Sr. No. 3,365, except as will presently appear. Each member of the lever 57 is provided with a forwardly extending arm 59 that is adapted at the limit of the operating movement of the lever 57 to bear upwardly against a suitable padded stop structure 60 fixed to the frame of the machine. Rearwardly extending parallel arms 61 on the driving lever 57 each preferably has a curved contact or rolling tread 62. A curved or rolling tread 63 on the over-lying lever 42 coacts with one of the treads 62, whereas the corresponding rolling tread 64

(Fig. 2) on the over-lying lever 48 coacts with the other tread 62 on the driving lever. In order to insure contact between the coacting lever arms 61, 42 and 48, I provide in the present construction a guide comb 65 secured at its upper end, as at 66, to the associated hanger 16. The coacting lever arms work in guide slots 67 in the comb and are thus maintained against relative lateral displacement. A depending link 68 is pivoted on a rivet 69 of each driving lever 57 and is forked at its lower end to coact with a segmental universal bar 70 which controls the escapement (not shown) for the carriage. The driving lever 57 also has an upright double arm 71 comprising two corresponding parts which straddle the bracket 16 and are united at their upper ends by a pivot pin 72. This double arm 71 is connected to the associated type bar 3 through mechanical devices which together with the main driving lever 57 constitute what has been hereinbefore referred to as a single train of driving connections including motion governing means having a momentum accumulator. Such means are effective to transmit a forward thrust to the type bar in a uniform manner whether actuated by one or the other associated keys 29 and 31. This train of connections includes a toggle comprising a double toggle link 73 made up of two correspondingly shaped members connected together but maintained spaced apart. The forward end portions of the members of this double link 73 extend on opposite sides of the type bar and are connected thereto by the pivot 11 which also connects the supporting link 9 to the type bar. A second double toggle member 74 is made up of two correspondingly shaped united parts which are maintained spaced apart. This double member 74 is pivoted at 75 to the forward end of the link 73 and extends on opposite sides of the hanger 16 and is supported to turn on a fixed pivot 76 carried by said hanger. A single link or lever arm 77 is connected at one end by the pivot 72 to the upright double arm 71 of the main driving lever. The arm 77 extends between the two members which constitute the toggle member 74 and is pivoted thereto at one end, as at 78, and moves the toggle 73, 74 to the substantially straight line position represented in Fig. 2, to apply printing pressure along the straight line of the toggle. Rigidly attached to the arm 77 is a comparatively heavy weighted member 79 which serves as a momentum accumulator for the actuating toggle 73, 74 when the latter is actuated by the main driving lever 57. After the depression of a printing key has been arrested, the momentum of the accumulator 79 will continue its movement to impart its energy to the toggle in order to complete the movement of the toggle members to the sub-

stantially straight line position, thereby completing the printing stroke of the type bar. It will be seen therefore that this momentum accummulator 79 is adapted to supply the final energy necessary to straighten the toggle 73, 74 when the type bar has substantially reached the printing position.

A contractile spring 80 is connected at one end to the bracket 16 and at the other end of 10 the rivet 69 on the driving lever 57 and serves to return the lever 57 and the parts connected therewith to the normal Fig. 1 position after each actuation, the key lever being independently arrested in its return 15 movement by the stop 44 or 58, or if desired by a padded stop or rod e. I have embodied novel means in the present construction associated with each type action for substantially noiselessly arresting the return movement 20 of the type bar and the train of driving connections therefor without rebound from the position of arrest, which I will now describe.

Referring more particularly to Figs. 3 and 25 4, it will be seen that a pair of toggle members or links 81 and 82 are united at their adjacent ends by a headed pivot pin 83. This pivot is riveted to the link 82 and works loosely in an inclined slot 84 in the link 81. 30 The width of this slot is such that the pin may be received therein with a free sliding fit. The slot extends longitudinally upwardly and forwardly towards the forward end of the link 81 at slightly less than a right angle to a straight line f (Fig. 3) that passes through the pivots 83, 85 and 86 of the links when the parts are in the normal position, shown in Fig. 3. The rear end of the link 81 has a corresponding slot 87 except that it 35 is inclined in the opposite direction from the slot 84. The slot 87 receives a headed pin 85 secured to the associated bracket or hanger 16 to which the pair of links is anchored. The headed pivot pin 86 is fixed to the 40 weighted member 79 and the link 82 which is pivoted on this pin is maintained spaced apart from the weight by a spacing sleeve 88. The forward end of the link 82 extends beyond its pivot 86 and forms a forwardly 45 extending stop projection or finger 89. This stop projection is adapted, under certain conditions, to coact with a laterally projecting stop pin 90 on the member 79, but is normally out of contact therewith. Gravity and 50 the reaction of the parts tend to maintain the parts so that each of the pivot pins 85 and 83 is normally seated in the upper end of its respective slots 84, 87, but under certain conditions there may be a change in these relations as will presently appear.

In the operation of the stop links, the return of the type bar and its train of driving connections from a projected position, such as is shown in Fig. 2, will tend to bring the 55 links 81 and 82 from the angular position

shown in said figure to a substantially straight-line position, shown in Fig. 3. When the parts reach this last mentioned position the links 81 and 82 will effect a dead center pull against the fixed pivot 85 and 70 arrest further movement of the parts in substantially a noiseless manner and without rebound. By arresting the return movement of the parts in the manner described the straightened links absorb the spring of the 75 moving parts and there is practically no rebound or noise produced in effecting the arrest. If for any reason the pivot pins 85 and 83 should, during the printing movement of the parts, become displaced from the upper ends of their respective slots 87, 84, then the strain exerted lengthwise of the links in arresting the parts will re-establish the pins in the upper ends of the slots. Although the links 81 and 82 are normally in substantially a straight-line position, as indicated in Fig. 3, they nevertheless will offer no resistance to the printing movement of the parts. This is due to the inclined slots 84 and 87 which enable the slotted ends of 90 the links and pins to receive a relative displacement to break the links from their straight-line position and prevent the links from locking the action against operation or from interfering with the printing movement of the parts.

The stops 89 and 90 prevent the links from accidentally jolting upwardly a material distance beyond the straight-line position in the return of the parts to normal position. By having the stops normally out of contact, and having them coact only occasionally when the connected ends of the links jolt up too far, I avoid the slight noise that might result by reason of the stops contacting at 105 every operation of the type bar.

In the present construction the alignment of the type bars is obtained by an inclined adjustment of the supporting arm 22 by 110 which the pivot 21 is carried. The degree of the angle of this adjustment in the present instance differs from that in my application Sr. No. 3,365, due to other changes made in the present type action, but the result obtained is the same. In the present instance I employ this one adjustment only of the member 22, and to effect it I provide inclined slots 91 and 92 in the member 22, the inclination of the slots corresponding to the line of adjustment of said member 22. Two guide pins 93 and 94, the latter being headed, are received in the slot 91, whereas two guide pins 95 and 96 are received in the slot 92, said pins projecting from the left-hand side of the associated bracket or hanger 16. An eccentric 97 is received in a slot 98 in the member 22, said slot extending lengthwise at substantially right angles to the slots 91 and 92. The eccentric 97 is provided with a hexagonal head by which it may be turned 125

to adjust the member 22 in the direction of the length of the slots 91 and 92 therein. A screw 99 carried by the bracket and on which the eccentric 97 turns is provided with a hexagonal head that clamps the eccentric in its adjusted position against the side of its bracket 16 and holds the member 22 in its adjusted position.

The arm 100, by which the pivot 13 of the link 9 is supported, may likewise be adjustably supported on the companion bracket 16 by pivoting the arm on the bracket at 101. The forward end of this arm 100 may have a longitudinally extending slot 102 therein, in which is seated an eccentric provided with a hexagonal head 103 and a binding screw having a corresponding head 104 to hold the eccentric in its adjusted position. The adjustment of the arm 100 to different set positions on the bracket 16 and around the pivot 101, results in raising or lowering the pivot 13 of the link 9. As hereinbefore indicated the adjusting means herein disclosed have the same objects in view as the corresponding adjusting means disclosed in my copending application, Sr. No. 3,365.

It has been explained that a separate supporting bracket or hanger 16 is provided for each type action. These brackets are radially disposed around the printing point, means being provided whereby each bracket, together with the parts of the type action carried thereby, may be individually introduced into and removed from the machine as a separate unit, and may receive an individual adjustment radially towards and from the printing point. The construction that enables these results to be obtained is the same as disclosed in my copending application, Sr. No. 3,365, and is as follows:

The forward horizontally disposed portion 105 of each bracket 16 is received in a radially disposed slot in the top of the member 2 of the machine frame. A depending projection 106 at the forward end of each bracket is received in a circumferential groove 107 in a screw 108 threaded into a tapped opening in the member 2. The rear depending end of each bracket 16 is slotted at 109 to receive the web 110 formed at the forward transversely slotted edge portion of a supporting member 111 secured to the base of the machine. The forward edge of the member 111 is segmental in form, corresponding to the arrangement of the set of brackets 16 at the lower end thereof and has interdental openings therein, each corresponding in width to the thickness of the associated bracket 16. This construction provides a firm interlocking support between each bracket 16 and the member 111 which holds the bracket against movement in every direction except that of its radial adjustment, effected by the companion screw 108.

A screw 112 coacting with a clamping plate 113 holds the companion bracket firmly in its adjusted position and enables the bracket with the parts carried thereby to be readily detached as a separate unit when desired.

It will be understood that by carrying the guide comb 65 of each type action on its associated supporting bracket or hanger 16, in accordance with my present invention, said guide combs do not interfere with the individual adjustment of each type action, or its individual introduction into or removal from the machine. The guide comb of each type action being individual thereto, and to the hanger or bracket by which the associated type action is supported, enables the above mentioned results to be readily attained.

The present invention contemplates effecting a relative case shift movement between the platen 114 and the type bars 3. Any suitable means may be employed for this purpose, such for example as the platen shifting mechanism disclosed in my application, Sr. No. 14,100 filed March 9, 1925. In the present construction a shift key 115 (Fig. 1) may be assumed to actuate suitable means (not shown) to shift the platen from the lower case full-line to the upper case dotted line position shown in Fig. 1. In Fig. 2 I have shown a lower case type 6 on the type block 4 at the printing point under an actuation of the key 31. A depression of the key 29 will bring a lower case type 7 on the type block 5 to the printing point when the platen is in the full-line Fig. 1 position. When the platen is shifted to the upper case dotted line position, then one of the upper case types 6^a or 7^a will be selectively moved to the printing point, depending on which of the two associated printing keys 29 or 31 is actuated.

In the operation of the machine a depression of the key 29 transmits a pull through the link 46 to operate the sublever 48. The rolling tread on this lever coacting with the companion rolling tread on the double arm 61 of the driving lever 57 gives a variable acceleration to the motion of the latter and also provides a lost motion connection between the levers 48 and 57. This lost motion is brought about when the motion of the lever 48, and the key 29 by which it is actuated, are brought to rest at the end of their stroke. At this time, the driving lever 57 and the parts connected therewith, including the type bar, are permitted to continue their operation independently of the lever 48 and under their own momentum, to effect an imprint without the impetus of the actuated key 29 and the parts connected therewith at the final portion of the printing stroke. The motion thus transmitted to the type bar is in the nature of a thrust exerted through the toggle members 73 and 74 push-

ing the type bar to the printing point and by the final expenditure of energy apply a powerful printing pressure. The printing operation of the type bar by an actuation of the key 31 is accompanied by a displacement of the pivotal center 12 of the supporting link 8, as shown in Fig. 2. This is accomplished by breaking the toggle 24, 26 from its substantially straight line position, shown in Fig. 1, to the position represented in Fig. 2, due to the actuation of the lever arm 42 with which the toggle has direct mechanical connection. This results in turning the lever 20 on its pivot 21 and lowering the supporting lever from the Fig. 1 to the Fig. 2 position, as hereinbefore explained, thereby changing the position of the pivotal center 12 of the supporting link 8 and causing the type bar to travel through a different curved path from that which it follows when actuated by the key 29, as indicated by a comparison of the dotted lines *b*, *c* in Fig. 1.

An actuation of the type bar by the key 29 produces a like movement of the single train of connections from the driving lever 57 to the type bar. In this instance, however, the toggle 24, 26 remains at rest in the substantially straight-line position, as indicated in Fig. 1, thereby holding the pivot 12 fixed against movement while the link 8 turns thereon. This results in the type bar moving in a curved path, indicated substantially by the dotted line *b* in Fig. 1, to print from one or the other of the types 7 or 7^a, depending on whether the platen is in the lower or upper case position to receive the impress of the corresponding type. A return movement of each type bar and the driving connections therefor to normal position, whether actuated by the associated key 29 or 31, is arrested by the links 81 and 82, as hereinbefore explained.

In the present construction I am enabled to employ a center type guide *d* that closely and effectively guides the type blocks both up and down, as well as sidewise, by reason of the hereinbefore described substantially straight-line movement given to the type block at the last portion of the printing movement, and while it is entering the type guide *d*, as will be clearly understood from an inspection of Figs. 1 and 7. As shown in Fig. 7 the fixed center guide *d* has upper and lower guide walls 116, 117 respectively and oppositely disposed side walls 118 and 119 which coat with each type block 4 or 5 as it squarely enters the guide and accurately directs it to the printing point, thus providing for accurate alignment. This is an important factor in a machine of this character and the said straight-line movement of the effective type block at the last part of the printing movement renders it feasible to thus accurately guide the type.

It will be seen that in the present con-

struction the supporting and guiding links 8 and 9 merely act as such at all times, the driving operation of the type bar being never effected through said links, and that whether the type bar be driven by the actuation of one or the other of the keys 29 or 31 such driving operation, as such, is effected independently of said links, and always through the separate and distinct single driving train from and including the lever 57, which exerts at all operations a thrust on the type bar to move it to printing position always in a uniform manner.

It will be understood, moreover, that the pivotal support for the link 9 is at all times maintained fixed during the printing operation, whether operating the type action from the key 29 or 31, and that the present construction as a whole provides a type action which has a light touch, is speedy in operation, and results to a high degree in a simple, uniform, accurate, noiseless and reliable printing operation that may be controlled by a standard keyboard.

While I have described in considerable detail the constructional form of the various members which go to make up each type action, I am aware that various changes may be made in the construction, and that certain parts may be employed without others, without departing from my invention as it is defined in the accompanying claims. However, the form of construction shown and described has proven reliable and efficient in use.

What I claim as new and desire to secure by Letters Patent, is:—

1. In a type action, the combination of a type bar, a pair of links for supporting the bar, a pair of printing keys, and means controlled thereby for actuating said type bar selectively to print from one or another type thereon depending on which key is actuated, the construction and arrangement of the parts being such that when the type bar is in printing position a straight line passing through the pivotal point of support of one of said links and through its point of pivotal connection with the type bar will intersect with a corresponding line drawn through the corresponding points of the other link, the said point of intersection being the same whether the type bar be actuated by one or the other of said printing keys.

2. In a type action, the combination of a type bar, a pair of links for supporting the bar, a pair of printing keys, and means controlled thereby for actuating said type bar selectively to print from one or another type thereon depending on which key is actuated, the construction and arrangement of the parts being such that when the type bar is in printing position a straight line passing through the pivotal point of support of one of said links and through its point of pivotal

- connection with the type bar will intersect with a corresponding line drawn through the corresponding points of the other link, the said point of intersection being approximately on a line tangent to the platen at the printing point and at substantially the same distance from the printing point whether the type bar be actuated by one or the other of said keys.
5. In a typewriting machine, the combination of a front stroke type bar, two keys for actuating said bar, and intermediate controlling means between said keys and type bar for moving the latter in a curved path in one direction to a point in front of but adjacent to the printing point by an actuation of one of said keys and for moving said bar in a curved path in the opposite direction to a point in front of but adjacent to the printing point by the actuation of the other of said keys, the effective type in both instances continuing its movement to the printing point substantially in a straight-line, said controlling means including a pivoted type bar supporting member, the pivotal center of which is at one elevation or another substantially in the same vertical line depending on which of the two keys is actuated.
10. 3. In a typewriting machine, the combination of a front stroke type bar, two keys for actuating said bar, and intermediate controlling means between said keys and type bar for moving the latter in a curved path in one direction to a point in front of but adjacent to the printing point by an actuation of one of said keys and for moving said bar in a curved path in the opposite direction to a point in front of but adjacent to the printing point by the actuation of the other of said keys, the effective type in both instances continuing its movement to the printing point substantially in a straight-line, said controlling means including a pivoted type bar supporting member, the pivotal center of which is at one elevation or another substantially in the same vertical line depending on which of the two keys is actuated.
15. 4. In a typewriting machine, the combination of a front stroke type bar pivotally mounted on a quaternal linkage and carrying a plurality of types, motion governing means articulated to said type bar and arranged to decelerate the final printing movement of said bar, a pair of printing keys, and controlling connections therefrom to actuate selectively said type bar, one of said keys being arranged to displace the axis of motion of one member of said linkage to a lower elevation than it normally occupies but substantially in the same vertical line.
20. 5. In a typewriting machine, the combination of a platen, a front stroke type bar carrying a plurality of types, a type guide, a plurality of printing keys, and means controlled thereby for selectively actuating said type bar to print from one or another of said types depending on which of said keys is actuated and to move the type bar through different curved paths to a position where the effective types reach a line of substantial coincidence before the platen is reached, said line of coincidence if projected extending substantially through the printing point and the axis of the platen and obtaining for a substantial portion of the final part of each path of advance of the active type into the type guide and towards the platen, said means including a type bar supporting link having its pivotal center displaceable to different elevations substantially in the same vertical line.
25. 6. In a type action, the combination of a type bar, a pair of links for supporting the bar, a pair of printing keys, and means controlled thereby for actuating said type bar selectively to print from one or another type thereon depending on which key is actuated, said means including means for shifting the pivotal center of one only of said links, the construction and arrangement of the parts being such that when the type bar is in printing position a straight line passing through the pivotal point of support of one of said links and through its point of pivotal connection with the type bar will intersect with a corresponding line drawn through the corresponding points of the other link, the said point of intersection being approximately on a line tangent to the platen at the printing point.
30. 7. In a typewriting machine, the combination of a front stroke type bar carrying a plurality of types, motion governing means articulated thereto and arranged to decelerate the final printing movement of said type bar, a plurality of printing keys, and controlling connections therefrom to actuate said type bar selectively through different paths, said connections including a type bar supporting link having its pivotal center at one elevation or another substantially in the same vertical line depending on which of the printing keys is actuated.
35. 8. In a type action, the combination of a type bar, a pair of links for supporting the bar, a pair of printing keys, and means controlled thereby for actuating said type bar selectively to print from one or another type thereon depending on which key is actuated, said means including means for shifting the pivotal center of one only of said links, the construction and arrangement of the parts being such that when the type bar is in printing position a straight line passing through the pivotal point of support of one of said links and through its point of pivotal connection with the type bar will intersect with a corresponding line drawn through the corresponding points of the other link, the said point of intersection being approximately on a line tangent to the platen at the printing point and at substantially the same distance from the printing point whether the type bar be actuated by one or the other of said keys.
40. 9. In a typewriting machine, the combination of a front stroke type bar pivotally mounted on a quaternal linkage and having two axes of motion, the type bar carrying a plurality of types, motion governing means articulated to the type bar and arranged to decelerate the final printing movement of said bar, a pair of printing keys, and controlling means therefrom to actuate selectively said type bar, said controlling means including means whereby one only of said axes of motion is positioned at one elevation or another substantially in the same vertical line.

line depending on which of the pair of printing keys is actuated.

10. In combination, a platen, a front stroke type bar carrying a plurality of types, a type guide, and means for moving said type bar so that certain of said types thereon will travel through curvilinear paths to the same point approximate to the printing position and will finish their movement through a substantially rectilinear path through the type guide and to the printing position with a decelerated movement, said means including a type bar supporting link having its pivotal center shiftable to different elevations substantially in the same vertical line.

11. In a type action, the combination of a type bar, a pair of links for supporting the bar, a pair of printing keys, and means controlled thereby for actuating said type bar selectively to print from one or another type thereon depending on which key is actuated, said means including motion governing means for decelerating the final printing movement of the type bar and substantially noiselessly pressing the type against the platen, the construction and arrangement of the parts being such that when the type bar is in printing position a straight line passing through the pivotal point of support of one of said links and through its point of pivotal connection with the type bar will intersect with the corresponding line drawn through the corresponding points of the other link, the said point of intersection being approximately on a line tangent to the platen at the printing point and at substantially the same distance from the printing point whether the type bar be actuated by one or the other of said keys.

12. In a typewriting machine, the combination of a front stroke type bar mounted for bodily movement and having a plurality of types fixed thereon; motion governing means connected with said type bar to decelerate the final printing movement of the type bar and for causing it to make an impact in a substantially noiseless manner; a plurality of printing keys; and means controlled thereby for controlling the paths of movement of said type bar to print selectively from one or another type thereon depending on which of said printing keys is actuated, said last mentioned means including a pair of type bar supporting links, and means controlled by one only of said printing keys for shifting the pivotal center of one only of said links from a point at one elevation to a point at a lower elevation but substantially on the same vertical line whereby the effective type may travel at the last portion of the printing movement in substantially a rectilinear path irrespective of which of the printing keys is actuated.

13. In a type action for typewriting machines, the combination of a front stroke

type bar having a plurality of types thereon; two independently operable actuating keys therefor; controlling means for controlling the path of movement of said type bar to print from one or another type thereon depending on which of said keys is actuated, said controlling means including a type bar supporting link, a lever on which said link is pivoted, means controlled by only one of said keys for shifting said lever so as to cause the point of pivotal connection of the link therewith to move from one point to another at different elevations but substantially on the same vertical line, said last mentioned means including a pair of toggle members normally maintained in a substantially straight-line holding position, and means controlled by one only of said keys for breaking the toggle members from such straight-line position, thereby actuating said lever; and additional means by which the type bar may be driven by the actuation of each of said keys.

14. In a type action, the combination of a type bar, a pair of links for supporting the bar, a pair of printing keys, and means controlled thereby for actuating said type bar selectively to print from one or another type thereon, depending on which key is actuated, said means including motion governing means for decelerating the final printing movement of the type bar and substantially noiselessly pressing the type against the platen, said first mentioned means also including means for shifting the pivotal center of one only of said links, the construction and arrangement of the parts being such that when the type bar is in printing position a straight line passing through the pivotal point of support of one of said links and through its point of pivotal connection with the type bar will intersect with a corresponding line drawn through the corresponding points of the other link, the said point of intersection being approximately on a line tangent to the platen at the printing point.

15. In a type action, the combination of a type bar, a pair of links for supporting the bar, a pair of printing keys, and means controlled thereby for actuating said type bar selectively to print from one or another type thereon depending on which key is actuated, said means including motion governing means for decelerating the final printing movement of the type bar and substantially noiselessly pressing the type against the platen, said first mentioned means also including means for shifting the pivotal center of one only of said links, the construction and arrangement of the parts being such that when the type bar is in printing position a straight line passing through the pivotal point of support of one of said links and through its point of pivotal connection with the type bar will intersect with a corre-

- sponding line drawn through the corresponding points of the other link, the said point of intersection being approximately on a line tangent to the platen at the printing point and at substantially the same distance from the printing point whether the type bar be actuated by one or the other of said keys.
16. In a typewriting machine, the combination of a platen; a front stroke type bar carrying a plurality of types; a pair of printing keys; and means controlled thereby for causing said type bar to move through different paths to selectively print from one or another type thereon in accordance with the printing key which is actuated, said means comprising a pair of links on which said type bar is supported, a supporting lever on which the supporting link nearest the type-carrying end of the type bar is pivoted, an angular lever, a link connecting said levers, and toggle members intermediate one of said keys and said angular lever and normally in a substantially straight-line holding position.
17. In a typewriting machine, the combination of a platen; a front stroke type bar carrying a plurality of types; a pair of printing keys; and means controlled thereby for causing said type bar to move through different paths to selectively print from one or another type thereon in accordance with the printing key which is actuated and to press the type in a substantially noiseless manner against the platen or the paper thereon, said means comprising a pair of supporting links for the type bar, a supporting lever to which one of said links is pivoted and which is connected to be actuated by only one of said keys, the construction and arrangement of the parts being such that the point of pivotal connection between said supporting lever and the link connected therewith moves from a point above a horizontal line passing through the fulcrum of said lever to substantially a corresponding distance below said line, and toggle members intermediate one of said keys and said supporting lever and normally in a straight-line holding position.
18. In a type action, the combination of a type bar, actuating means therefor, and means in addition to said actuating means for substantially noiselessly limiting the return motion of said type bar to normal position and preventing a rebound of the type bar from such position, said limiting means comprising toggle members which are moved substantially to straight-line position by the return motion of the type bar and normally remain in such position.
19. In a type action, the combination of a type bar, actuating means therefor, and means in addition to said actuating means for limiting the return motion of said type bar to normal position and preventing a re-
- bound of the type bar from such position, said limiting means comprising toggle members which are moved substantially to straight-line position by the return motion of the type bar, and means which enable 70 said toggle members to break from said substantially straight-line position when the type bar receives a printing movement by its actuating means.
20. In a type action, the combination of 75 a type bar, actuating means therefor, a pair of links pivotally united and connected at one end to the type-bar actuating-means and anchored at the other end to a relatively fixed part of the machine, said links assuming a substantially straight-line position on the return of the type bar to normal position, thereby arresting the return movement of the parts.
21. In a type action, the combination of 80 85 a type bar, and means for limiting the return motion of said type bar to normal position comprising toggle members which are moved substantially to straight-line position by the return motion of the type bar, and means which enable said toggle members to break from said substantially straight-line position when the type bar receives a printing movement, said last mentioned means comprising a slotted bearing for one of the 90 pivots of said toggle members, said slotted bearing extending longitudinally at an angle to a straight-line passing substantially through the pivots of said toggle members when the latter are in a straight-line position.
22. In a type action, the combination of 95 100 a type bar, actuating means therefor, and means in addition to said actuating means for substantially noiselessly limiting the return motion of said type bar to normal position and for preventing a rebound thereof from normal position, said limiting means comprising a link pivoted at one end to a relatively fixed point and operatively connected at the other end with a part of the type action, said link being displaced during the return movement of the parts to a position where it dead centers against said fixed pivot and thus arrests the return movement of the type bar to normal position, the said link normally remaining substantially in said dead centered position.
23. In a type action, the combination of 105 110 115 a type bar, and means for limiting the return motion of said type bar to normal position comprising toggle members which are moved substantially to straight-line position by the return motion of the type bar, and means which enable said toggle members to break from said substantially straight-line position when the type bar receives a printing movement, said last mentioned means comprising slotted bearings for pivots of 120 125 130 said toggle member, each slotted bearing ex-

tending longitudinally at an angle to a straight-line substantially through the pivots of said toggle members when the latter are in a straight-line position.

24. In a type action, the combination of a type bar; actuating means therefor; and means in addition to said actuating means for substantially noiselessly limiting the return motion of said type bar to normal position and for preventing rebound therefrom, said limiting means comprising toggle members which are moved substantially to straight-line position by the return motion of the type bar, and means for preventing 10 said toggle members from moving in one direction any considerable distance beyond the straight-line position, said last mentioned means coming into action only when said toggle members pass beyond the straight-line position.

25. In a type action, the combination of a type bar, actuating means therefor, and means in addition to said actuating means for substantially noiselessly limiting the return motion of said type bar to normal position and for preventing rebound thereof from such position, said limiting means comprising toggle members which are moved substantially to straight-line position by the 25 return motion of the type bar, and co-acting rigid stops which are brought into co-operation with each other only when the toggle members pass beyond the straight-line position in their return movement, thus preventing 30 said toggle from moving a substantial distance in one direction beyond said straight-line position.

26. In a type action, the combination of a type bar; actuating means therefor including motion governing means operating to decelerate the final portion of the printing movement of the type bar; and means for arresting the return movement of the type bar and governing means to normal position, 40 said arresting means comprising a pair of pivotally connected links pivoted at one end to the motion governing means and at the other end to a fixed part, the links being movable substantially to a straight-line position on the return of the type bar to arrest 45 the parts in normal position.

27. In a type action, the combination of a type bar; actuating means therefor including motion governing means operating to decelerate the final portion of the printing movement of the type bar; and means for arresting the return movement of the type bar and governing means to normal position, said arresting means comprising a pair 55 of pivotally connected links pivoted at one end to the motion governing means and at the other end to a fixed part, the links being movable substantially to a straight-line position on the return of the type bar to arrest 60 the parts in normal position, and

means for preventing said links when in a straight line position from interfering with a printing movement of the governing means and type bar.

28. In a type action, the combination of a type bar; actuating means therefor including motion governing means operating to decelerate the final portion of the printing movement of the type bar; and means for arresting the return movement of the type 70 bar and governing means to normal position, said arresting means comprising a pair of pivotally connected links pivoted at one end to the motion governing means and at the other end to a fixed part, the links being movable substantially to a straight-line position on the return of the type bar to arrest the parts in normal position, a stop on one of said links and a co-acting stop on said motion governing means, said stops co-acting 80 when the links move slightly beyond the straight line position in the return movement of the parts.

29. In a type action, the combination of a separately adjustable and detachable supporting hanger or bracket, a type bar carried thereby, a plurality of co-operative key controlled actuating devices for the type bar carried by said bracket, and a guide carried by and adjustable and detachable with said 90 bracket and coacting with said co-operative actuating devices to prevent them from being displaced out of co-operative relation.

30. In a type action, the combination of a separately adjustable and detachable supporting hanger or bracket, a type bar carried thereby, a plurality of co-operative key controlled actuating devices for the type bar carried by said bracket, and a guide comb secured to said bracket and adjustable and 105 detachable therewith, said actuating devices working in the slots of said guide comb and being thus held against lateral deflection and maintained in co-operative relation.

31. In a type action, the combination of a separately adjustable and detachable supporting hanger or bracket; a type bar carried thereby; a plurality of co-operative key controlled actuating devices for the type bar carried by said bracket, said actuating devices comprising two key controlled sub-levers, and a main driving lever having two lever arms with which said sub-levers co-act with a rolling action thereon; and a guide comb secured to said bracket and receiving 110 in the guide slots therein said sub-levers and lever arms to maintain them in proper co-operative relation, said guide comb being adjustable and detachable with said bracket.

32. In a typewriting machine, the combination of a separately adjustable and detachable bracket or hanger; a pair of supporting links carried by said bracket; a type bar carried by said supporting links; two printing keys; actuating means between said 125

printing keys and type bar comprising a pair of sub-levers each separately controlled by one of said printing keys, and a main driving lever having a pair of lever arms 5 with which said sublevers coact with a rolling action; and a guide comb secured to said bracket and in the guide slots in which said co-operative sublevers and lever arms work

and are held against relative lateral displacement, said guide comb being adjustable 10 and detachable with the bracket.

Signed at Middletown, in the county of Middlesex, and State of Connecticut this 20th day of June, A. D. 1925.

GEORGE G. GOING.
